MECHANISM FOR CHANGING AND GOVERNING THE SPEED OF ENGINES

Filed July 20, 1934

UNITED STATES PATENT OFFICE

2,001,590

MECHANISM FOR CHANGING AND GOVERN-
ING THE SPEED OF ENGINESWilliam R. Spiller, Cleveland, Ohio, assignor to
The White Motor Company, Cleveland, Ohio,
a corporation of Ohio

Application July 20, 1934, Serial No. 736,224

3 Claims. (Cl. 123—103)

This invention relates to internal combustion engines, and more particularly to mechanism for changing and governing the speed thereof.

It is an object of this invention to provide an efficient speed-change mechanism of the type which comprises a governor for limiting the engine speed.

It is a further object of this invention to provide a speed-change mechanism of the type above defined which embodies but a single throttle valve.

It is a further object of this invention to provide a speed-change mechanism of the type specified in the first object which comprises means for notifying the operator of the initiation of governor control.

Other objects will appear in the following description when read in connection with the accompanying drawing, in which:

Figure 1 is a side elevation of an automobile engine equipped with a speed-change mechanism embodying the present invention, certain parts being broken away and others being shown in section for the purpose of disclosing internal construction.

Figure 2 is a perspective view of a portion of the throttle control mechanism, and

Figure 3 is a fragmentary sectional view of the mechanism shown in Figure 2 and of an adjacent portion of the engine, the section being taken on line 3—3 of Figure 1.

Referring to the drawing, the numeral 10 indicates an internal combustion engine, and the numeral 11 the floor boards of an automobile of which the engine 10 constitutes a part.

The fuel induction system of the engine 10 comprises an inlet manifold 12, an inlet pipe 13 leading downward from the manifold 12, and a carburetor 14 mounted on the lower end of the inlet pipe 13.

The carburetor 14 is constructed with a conventional throttle valve 15 of the butterfly type equipped with an operating lever 16 located on the rear side of the carburetor. The lever 16 is operatively connected through a mechanism P with a governor 17 secured to the side of the engine and with a throttle control mechanism Q mounted on the floor boards 11.

The mechanism P comprises three levers 18, 19 and 20 fulcrumed on a screw 21 mounted in the side of the engine, the lever 19 being held in position with respect to the levers 18 and 20 by means of spacer-washers 22. The lever 18 and the upper arm of the lever 19 are formed with laterally extending parts 23 and 24 which are brought into engagement by the governor 17 as

hereinafter explained; and the lever 20 and the lower arm of the lever 19 are formed with similar parts 25 and 26 which are maintained in engagement at speeds below governor control by a tension spring 27 connecting the lower ends of the levers.

The lever 18 is connected to the operating mechanism of the governor 17 by a pivotally attached rod 28, the lever 19 to the operating lever 16 of the throttle valve 15 by a pivotally attached rod 29, and the lever 20 to the throttle controlled mechanism Q by a pivotally attached rod 30.

The governor 17 comprises a casing 31 mounted upon a seat formed on the side of the engine. Mounted within the casing 31, there is a rotatable shaft 32 driven from the engine camshaft by means of gears 33 and 34; and rigidly attached to the shaft 32 and having a bearing on a seat 35 formed on the base of the casing 31, there is a member 36 which supports a pair of pivotally mounted governor weights 37 formed with inwardly extending arms 38.

Slidably mounted upon the upper end of the shaft 32 there is a sleeve 39 formed at its lower end with a concave surface upon which the arms 38 exert an upward camming action on outer movement of the weights 37. The sleeve 39 is pressed downward against the arms 38 of the governor weights 37 by a spiral spring 40, which prevents upward movement of the sleeve 39 below a certain predetermined engine speed. The sleeve 39 is connected to the upper end of the rod 28 leading from the mechanism P by a lever 41 fulcrumed on the casing 31.

The governor is so constructed that it operates to move the lever 18 into engagement with the lever 19 for all conditions of load within a small range of speeds spaced below the highest allowable engine speed by a small speed change, and following the engagement of the levers 18 and 19 to resist further throttle opening movement of the lever 19 with a force capable of causing separation of the levers 19 and 20. It is so designed and coordinated with the other parts of the throttle actuating mechanism that the introduction into the throttle actuating mechanism of the initial tension of the spring 27 following separation of the levers 19 and 20 will operate to increase the opening of the throttle valve only a small amount, and the increase in tension set up therein by moving the mechanism Q to the limit of its throttle opening movement but a small added amount, provision being made through the proper adjustment of parts such that the speed of the engine can under no condition be increased be-

yond the speed selected as the highest allowable speed.

The throttle control mechanism Q comprises a bell crank lever 42 pivotally supported from the floor boards 11 by means of a member 43, and a plunger 44 pivotally attached to the upper end of the lever 42 and extending upwardly through the floor boards for actuation by the operator of the vehicle. The lever 42 is formed with a stop 45 designed for engagement with the floor boards 11, and is pivotally connected at its lower end to the rod 30 leading from the lever 20 of the mechanism P. A tension spring 46 attached at one end to the rod 30 and at its other end to the side of the engine urges forward motion of the rod 30 to maintain the lever 42 in position with the stop 45 engaging the floor boards.

The adjustment and construction of the throttle mechanism just described is such that the parts thereof occupy positions as illustrated for idling speed of the engine.

Assuming that the engine is running at idling speed, depression of the plunger 44 will act through the lever 42 and the rod 30 to cause rearward rotation of the lever 20, and through the spring 27 the lever 19 and the rod 29 to produce rotation of the throttle valve 15 towards an open position. As the speed of the engine is increased through depression of the plunger 44, the speed effecting governor operation will be reached, following which the sleeve 39 will be moved upward by the camming actions of the arms 38. The resulting upward movement of the sleeve 39 acting through the lever 41 and the rod 28 will cause the lever 18 to be rotated in an anti-clockwise direction, and at an engine speed slightly greater than that initiating upward movement of the sleeve will bring the part 23 on the lever 18 in engagement with the part 24 on the lever 19 to check further movement of the latter lever in a clockwise direction. Due to the design of the governor as heretofore set forth, the last described movement will take place under all conditions at a speed less than the allowable engine speed.

Further depression of the plunger 44 following engagement of the stops 23 and 24 on the levers 18 and 19 will operate to move the lever 20 away from the lever 19 adding to the pull on the rod 30 the tension of the spring 27, and notifying the operator that governor control has been initiated. A portion of the tension of the spring 27 will also be added by way of the parts 18, 28, and 41 to the spring load on the governor sleeve 39. The added load on the sleeve 39 will act to depress the sleeve a small amount, and in so doing will move the arm 18 in a clockwise direction with the result that the spring 27 will act to move the arm 19 in a like direction to further increase the throttle opening. As the plunger 44 is further depressed, the tension of the spring 27 will be increased, increasing the load on the sleeve 39 and producing further opening movement of the throttle valve. In accordance with the manner in which the governor is designed and coordinated with the other parts of the throttle actuating mechanism the maximum speed attained by depressing the plunger 44 to the limit of its movement will fall within a small range of engine speeds having as its upper limit the speed selected as the highest allowable engine speed.

If the pressure on the plunger 44 is released after reaching a point where the spring 27 has been placed under tension, the lever 20 will be first moved under the influence of the springs 27

and 46 to bring the part 25 into engagement with the part 26 on the lever 19, after which the levers 20 and 19 will be rotated together in a clockwise direction under the influence of the spring 46 moving the valve 15 toward a closed position. As the speed of the engine is decreased, the speed will be reached where the force of the spring 40 will overcome the upward thrust of the arms 38 of the weights 37, following which the sleeve 39 will be moved downward by the spring 40 moving the lever 18 away from the lever 19 back to its original position.

From the foregoing description, it will readily be seen that through a certain range of speeds the throttle valve 15 will be directly controlled by the throttle control plunger 44, and that above such range the governor will act to decrease the rate of speed produced by depression of the plunger, the construction and design of the mechanism being such that the speed of the engine can never exceed a predetermined limit.

Although the foregoing description is necessarily of a detailed character, in order that the invention may be completely set forth, it is to be understood that the specific terminology is not intended to be restrictive or confining, and that various rearrangements of parts and structural details may be resorted to without departing from the scope or spirit of the invention as herein claimed.

I claim as my invention:

1. The combination in an internal combustion engine, of a throttle valve for said engine, a governor associated with said engine designed to transmit movement at a predetermined engine speed, a throttle actuating lever, a movable member operatively connected to said throttle valve, a second movable member operatively connected to said governor arranged to be moved thereby upon an increase of speed above the aforesaid predetermined speed in an opposite direction to said first member in causing an increase in speed, and being further arranged in such a manner that it is maintained out of engagement with said first named member at speeds below the aforesaid predetermined speed and brought into engagement with said first member as the engine speed is increased above the aforesaid predetermined speed, a third movable member operatively connected to said throttle actuating lever arranged to move in the same direction as said first member in opening and closing the throttle valve, means carried by said first and third members designed for abutting engagement arranged in such a manner that movement of said throttle actuating lever in a direction to open the throttle valve tends to cause separation of said means, and resilient means connecting said first and third members urging engagement of the engaging means carried by such members, said resilient means being designed and tensioned to maintain the aforesaid engaging means in engagement in the absence of interference by said second member, but permitting separation of said engaging means following the point in movement of said first and third members in opening the throttle valve at which further movement of said first member is opposed by the actuating force of the governor acting through said second member.

2. The combination in an internal combustion engine, of a throttle valve for said engine, a governor associated with said engine designed to produce movement of correlated parts at a predetermined engine speed, a throttle actuating member,

- a lever mounted on a fixed fulcrum operatively connected to said throttle valve, a movable member operatively connected to said governor arranged to be moved thereby upon an increase 5 of speed above the aforesaid predetermined speed in an opposite direction to said first lever in causing an increase in speed, and being further arranged in such a manner that it is maintained out of engagement with said first lever at speeds 10 below the aforesaid predetermined speed and brought into engagement with said first lever as the engine speed is increased above the aforesaid predetermined speed, a second lever mounted on said fulcrum operatively connected to said throttle 15 actuating member, the arrangement of said second lever and of the means connecting it with said throttle actuating member being such that movement of said throttle actuating member in a direction to open the throttle tends to cause 20 separation of said first and second levers, means on said first and second levers designed for abutting engagement, and resilient means placed under tension connecting said first and second levers acting to hold the engaging means on said levers 25 in engagement, the tension in said resilient means being sufficient to cause said first and second members to move together in a direction to open the throttle valve, but being insufficient to prevent separation of said first and second levers 30 when further movement of said first lever is opposed by the actuating force of the governor acting through said movable member.
3. The combination in an internal combustion engine, of a throttle valve for said engine, a governor associated with said engine designed to produce movement of correlated parts at a predetermined engine espeed, a throttle actuating member, a lever mounted on a fixed fulcrum operatively connected to said throttle valve, a sec- 35 ond lever mounted on said fulcrum operatively connected to said governor, said second lever being connected to said governor in such a manner as to be moved thereby upon an increase of speed above the aforesaid predetermined speed in an opposite direction to said first lever in causing an increase in speed, means on said first and second levers designed for abutting engagement, the connection between said first lever and said throttle valve and the connection between said second lever and said governor being so coordinated that the aforesaid engaging means are maintained out of engagement at speeds below the aforesaid predetermined speed, and brought into engagement as the engine speed is increased 15 above the aforesaid predetermined speed, a third lever mounted on said fulcrum, means connecting said third lever with said throttle actuating member, the arrangement of said third lever and the means connecting it with said throttle actuating member being such that movement of said throttle actuating member in a direction to open the throttle tends to cause separation of said first and third members, means on said third lever and said first lever designed for abutting engagement, and resilient means placed under tension connecting said first lever and said third lever acting to hold the engaging means on said first and third levers in engagement, the tension in said resilient means being sufficient in the absence of the interference by said second lever to cause said first and third levers to move together in a direction to open the throttle valve, but insufficient to prevent separation of said first lever and said third lever when further movement of said first lever is opposed by the actuating force of said governor following engagement of the engaging means on said first and said second levers.

WILLIAM R. SPILLER. 40
